(57) **CLAIM**

The ornamental design for an implantable cardiac monitor as shown and described.

DESCRIPTION

FIG. 1 is a perspective view of an implantable cardiac monitor according to a first embodiment of the present design;

FIG. 2 is front elevation view of the implantable cardiac monitor of FIG. 1;

FIG. 3 is a rear elevation view of the implantable cardiac monitor of FIG. 1;

FIG. 4 is a left side view of the implantable cardiac monitor of FIG. 1;

FIG. 5 is a right side view of the implantable cardiac monitor of FIG. 1;

FIG. 6 is a top plan view of the implantable cardiac monitor of FIG. 1;

FIG. 7 is a bottom plan view of the implantable cardiac monitor of FIG. 1;

FIG. 8 is a perspective view of an implantable cardiac monitor according to a second embodiment of the present design;

FIG. 9 is front elevation view of the implantable cardiac monitor of FIG. 8;

FIG. 10 is a rear elevation view of the implantable cardiac monitor of FIG. 8;

FIG. 11 is a left side view of the implantable cardiac monitor of FIG. 8;

FIG. 12 is a right side view of the implantable cardiac monitor of FIG. 8;

(Continued)

FIG. 13 is a top plan view of the implantable cardiac monitor of FIG. 8; and,

FIG. 14 is a bottom plan view of the implantable cardiac monitor of FIG. 8.

The dot-dash lines immediately adjacent the shaded areas depict the bounds of the claimed design, while all other broken lines are directed to environment. The broken lines form no part of the claimed design. The oblique line shading in FIG. 1, FIG. 2, FIG. 3, and FIG. 4 depict a transparent surface.
